Elias S. Cornell, Evanston, Ill., assignor to The Delta-Star Electric Company, Chicago, Ill., a corporation of Illinois

Application June 5, 1940, Serial No. 338,860

27 Claims. (Cl. 200—48)

The present invention relates to electric switches, and particularly to disconnect switches for use under high current conditions.

Switches of this type are ordinarily not used for breaking or interrupting current flow in a circuit, since they are not designed to withstand the effects of the arcs formed by breaking a circuit. Rather they are used to provide a definite break in the circuit after the circuit has been opened by other means such as a circuit breaker.

Due to the peculiar construction of disconnect switches it is a recognized difficulty in connection with them to secure good electrical contact. To secure good electrical engagement the contacts must be under considerable pressure, but when they are under pressure it is difficult to open and close the switch. If the contacts are made to fit loosely in an effort to provide for easy opening and closing, secure electrical engagement is sacrificed.

I have overcome this difficulty in a novel manner by the invention herein disclosed. The device of my invention comprises a simple means for providing easy opening and closing operations, and when the switch is closed the contacts will be in good electrical engagement.

I have found that a high pressure contact in a localized region between the contacting surfaces will produce good results in carrying current with little loss in efficiency even when the region of contact is less in normal current carrying capacity than the conductors which are connected. It has been found impracticable to attempt to attain firm engagement between large areas because the total force necessary to do so is much greater than that necessary for small areas, hence the use of high pressure, small-area contacts. Also in the case of large-area contacts inaccuracies in alignment prevent engagement throughout the whole areas. Another objection to large-area contacts is that, when their surfaces become uneven and weather-beaten, firm engagement is next to impossible, but when the areas of contact are small and subjected to great pressure the bodies of the contacts are made to engage, despite their uneven surfaces.

I have developed a device which embodies the advantageous features mentioned above and overcomes the objections mentioned. By a simple movement of the operating mechanism the switch can be closed with the switch blades passing freely over the stationary contacts, and by continuing the movement of the operating mechanism the contacts are brought under pressure. Conversely, in the opening operation, on the initial movement of the operating mechanism, the pressure on the contacts is released and continued movement will open the switch.

As one feature of my invention I employ multiple current paths which add to the current

carrying capacity of the switch, and the single operating mechanism of the switch is designed to operate the plurality of switch blades in the same manner in which it operates a single blade.

5 In the preferred form of the invention, I propose to establish the pressure on the contacts by means of a cam and lever arrangement. The cam surface is of small inclination, by means of which fact a great pressure can be exerted on the contacts.

An object of my invention is to provide for applying and releasing contact pressure between separable switch members respectively after and before movement thereat to and from the switch 15 closed position in a new and improved manner.

Another object of my invention is to provide for simultaneously applying pressure to urge each of a pair of switch members toward the other into contact engagement with a switch member 20 therebetween and for simultaneously releasing the switch members from the contact engagement with the application and release of contact pressure being effected respectively, subsequently and prior to relative movement of said switch members to and from the switch closed position.

25 Another object of my invention, in an alternate form, is to provide for maintaining one end of a pair of switch members in constant contact engagement with a stationary switch member therebetween, while bringing the other end of the pair of switch members into and out of contact engagement with the other stationary switch member.

Other objects and advantages will appear to 30 those skilled in the art on reference to the following detailed description taken in conjunction with the accompanying drawings, in which:

Figure 1 is a side elevational view of one form of my invention;

Figure 2 is a bottom view of the device shown in Figure 1;

Figures 3 and 4 are similar to Figure 1 showing the operating parts in different positions;

Figure 5 is a side elevational view of another 45 form of my device;

Figure 6 is a top view of the device shown in Figure 5;

Figures 7 and 8 are views similar to Figures 5 and 6 respectively, showing the operating parts 50 in different positions;

Figure 9 is a view similar to Figures 5 and 7 showing the switch in partially open position;

Figure 10 is an enlarged developed view of the cam member of Figure 1 taken approximately on the line 10—10 of Figure 1;

Figure 11 is an enlarged developed view of the cam member of Figure 5 taken approximately on the line 11—11 of Figure 5;

Figure 12 is a side elevational view of a modified form of my invention;

Figure 13 is a section taken on the line 13—13 of Figure 12;

Figure 14 is a side elevational view of another form of my invention; and

Figure 15 is a section taken on the line 15—15 of Figure 14.

Referring now in detail to the drawings, I have shown in Figures 1 to 4, inclusive, one form of disconnect switch which comprises two conducting lines or current paths, a type often found advisable in use with extremely high currents, the plurality of paths providing greater current carrying capacity and lessening the likelihood of overheating.

Each current path of the switch comprises conductor bars 12 and 14 terminating in stationary contacts 12' and 14' respectively, and a contact bar indicated generally by the reference numeral 15 which is operable to open and closed position of engagement between the conductor bars. The construction of the two current paths is similar and a description of one may be duplicated for the other. The two conductor bars 12 are connected to a single line, as are the two conductor bars 14, and the two contact bars 15 are operable in unison into and out of engagement with the respective conductor bars.

A frame, indicated by the numeral 16, is bolted or otherwise suitably secured between the bars 12. Between the bars 14 is a bar support 17, secured thereto by bolts or other suitable means by which the switch as a whole may be supported.

Each of the contact bars is made up of two separate switch blades, 19 and 20, one on either side of each of the conductor bars 12 and 14, and the two are adapted to move as a unit into and out of engagement with the conductor bars. In the preferred embodiment the contact bars 15 are pivoted to rotate freely on a shaft 18 which is supported by frame 16 and conductor bars 12 and which in turn supports switch operating mechanism to be described later. At each end of each of the switch blades 19 and 20, is an elongated indented area 21, extending transversely of the blade and stamped in the outer surface thereof. By this stamping operation a projection 22 is formed on the inner side of the blade opposite the indented area. It will be seen that the location of these projections 22 is such that they will engage the conductor bars 12 and 14 when the switch is closed.

At each end of the contact bar 15 is a pair of leaf springs 24, 24' and 25, 25', the springs of each pair being mounted on opposite sides of the switch blades 19 and 20. Each spring member in its preferred form is built up of a plurality of leaves; this adds to the strength of the spring and enables it to withstand the pressure under which it is put, but it is to be understood that a single leaf may be employed if so desired. Spring clamps 29 are positioned over the springs and are provided with down-turned flanges 30 to hold the springs against displacement. The spring assembly is then held in place by studs 27 which pass loosely through openings in the switch blades 19 and 20, and through the springs and spring clamps. The springs can thus be actuated without any binding effect between studs 27 and the switch blades. The springs 24, 24' and 25, 25' are turned inwardly at their outer ends as indicated at 31 to fit into the indented areas 21.

The springs 24, 24' and 25, 25' and the switch blades 19 and 20, are each slotted at their outer ends as shown at 23. This feature adds to the flexibility of both the springs and the switch

blades and aids in securing engagement between the contacts of the switch.

A rotatable cam member 32 is disposed between the switch blades 19 and 20 and is pivoted to rotate freely on pin 34 carried by the switch blades. The cam member 32 is in the form of a disc and is generally circular in formation and provided with a lever 35 for operating it. The cam member 32 is provided with four cam surfaces 36, 36' and 37, 37' which are arcuate in shape with their center of curvature at the center of the cam member and disposed about the periphery of the cam member. Cam surfaces 36 and 36' are disposed on opposite sides of the cam member 32 directly opposite to each other, as are the two surfaces 37 and 37', and the surfaces 36, 36' are disposed diametrically opposite the surfaces 37, 37'. Balls 39 are positioned between the cam surfaces 36, 36' and 37, 37' and their corresponding springs, 24, 24' and 25, 25'. These balls are held in place in openings 40 in the switch blades 19 and 20 and act as thrust members between the cam surfaces and the springs.

Reference is here directed to Figure 10 which shows to best advantage the shape of the cam member 32. When the cam member is rotated clockwise the ball thrust members 39 ride up the cam surfaces and onto the widened portion 41 of the cam member. This action spreads the springs 24, 24' and 25, 25', the reaction of each caused by the thrust being expended on its corresponding spring through the spring clamps 29 and studs 27, causing the ends 31 of the springs to be forced inwardly and bias the switch blades into high pressure engagement with the conductor bars 12 and 14; and of course when the action is reversed, i. e., the cam member 32 rotated counterclockwise, the thrust members 39 ride down onto the narrow portion 42 of the cam member releasing the pressure on the springs. Due to the position of the cam surfaces 36, 36' and 37, 37', the action on all the springs is simultaneous, i. e., pressure is exerted on all together, and it is released on all together.

The frame 16 is in the form of a U-shaped bracket, indicated at 44, which is bolted at 45 to the conductor bars 12 and is provided with a web 46 extending between the arms thereof. Mounted on the bracket 44 are two links 49 and 50 pivoted at 51 and 52 respectively. A third link 54 is mounted on the two links 49 and 50 at points 55 and 56 respectively, and is connected to the lever 35 of the cam member 32 at 57. The link 54 is provided with downwardly extending lugs 59 to which is connected a connecting rod 60 by means of a universal joint 61. The other end of the connecting rod 60 is connected through a universal joint 62 to a crank arm 64 attached to a shaft 65. The shaft 65 is mounted in a ball bearing 66, or any other suitable bearing, supported by the web 46 and is adapted to be operated by any suitable power or hand operating mechanism.

Operation of the switch is best shown in Figures 3 and 4. Rotation of the operating shaft 65 will swing the crank arm 64 which, through the connecting rod 60, will actuate the link 54 thereby operating the cam member 32 and ultimately the switch itself. The link 54 is designed so that in its movement from the left to the right, as shown in Figure 3, it will first rotate the cam member 32 in a counterclockwise direction to release the pressure on the springs without moving the switch blades 19 and 20, after which continued movement of the link 54 will swing the blades about their pivot on the shaft

18, to the position shown in Figure 4. The arcs through which the links 49 and 50 swing are indicated at 49' and 50' respectively, and the arc through which the lever 35 of the cam member 32 swings in its initial opening movement is indicated at 35'. The link 50 is longer than the link 49, and due to this fact the third link 54 is subjected to a compound movement while the links 49 and 50 have a simple rotary movement. As the link 54 is moved from the left to the right (Figure 3) the links 49 and 50 are rotated counterclockwise, and, practically speaking, they establish a parallel movement, with the effect that the initial movement of the link 54 is substantially rectilinear. This action enables initial actuation of the cam member 32 without exerting any force on the switch blades in one direction or the other. Obviously the point of connection 57 between the link 54 and the lever 35 must move precisely in the path of the arc 35' to avoid any movement of the switch blades during operation of the cam member 32. This is brought about by the relative lengths of the links 49 and 50. Since these two links are of different lengths, they guide the third link 54 so that the point 57 moves in the path of the arc 35' to substantially the position shown in Figure 3. This modification of the movement of the link is the only variation from its rectilinear movement. The usual play present in such connections is ample to provide for inaccuracies encountered in practical operations of the device. With the cam member 32 in the position shown in Figure 3 the thrust members 39 have ridden down the cam surfaces, releasing the pressure on the springs 24, 24' and 25, 25'. Although the switch is here shown in closed position, the pressure on the switch blades is released and the switch can be easily opened. Continued movement of the link 54 from the left to the right (as viewed in Figure 3) will swing the links 49 and 50 further in a counterclockwise direction until they reach their positions shown in Figure 4. As the pivot point 56 of the link 50 approaches its position shown in this figure it becomes virtually a fixed pivot for the link 54 causing the latter to act as a lever about this point and thereby open the switch.

It is, of course, obvious that the reverse of this action takes place in the closing operation of the switch. In the initial closing movement the link 54, acting as a lever, pivots in a clockwise direction swinging the switch to closed position when the link 54 is in the position shown in Figure 3. Thereafter movement of the link to the left (as viewed in this figure) rotates the cam member 32 in a clockwise direction thereby bringing the switch blades into high pressure engagement with the conductor bars, without then exerting any force of translation on the switch blades in one direction or the other.

A modified form of my invention is shown in Figures 5 to 9, inclusive. In this form is shown a single conductor or current path which comprises conductor bars 70 and 71 rigidly mounted on insulator stacks 72 and 73, and terminating in stationary contacts 70' and 71'. A movable contact bar indicated generally by the reference numeral 75 and comprising two blades 76 and 77 constitutes the switching element for bridging the conductor bars. In the preferred form the blades 76 and 77 are pivoted for free rotation on a shaft 78 supported by the conductor bar 70. The conductor bars 70 and 71 are secured to their respective insulator stacks by means of

brackets 79 and 80 fitted over the bottom edges of the conductor bars.

The device of this form is essentially the same as the previous embodiment except that this is a single conductor switch, and it employs a different form of operating mechanism.

The two switch blades 76 and 77 are positioned one on either side of each of the stationary contacts 70' and 71', and the blades at 10 each end thereof are provided with elongated indentations 81, formed by punching or any other desired method. The indentations are formed on the outer surfaces of the switch blades, and result in projections 82 of the same general configuration on the inner surfaces of the blades which are adapted to engage the stationary contacts.

As in the previous embodiment, a number of 20 springs are employed for bringing the switch blades into engagement with the stationary contacts. At each end of the contact bar is a pair of springs, each spring operable to engage one end of one of the switch blades 76 and 77. Springs 84, 84' are positioned on opposite sides 25 of the switch blades and are adapted to bring the ends of the switch blades into high pressure engagement with the stationary contact 70', and the springs 85, 85' are also positioned on opposite sides of the switch blades, and are adapted 30 to bring the ends of the switch blades into high pressure engagement with the stationary contact 71'. The pair of springs 84, 84' are held in place by spring clamps 86, and a stud 87 passing loosely through the switch blades and the springs 35 and clamps. The pair of springs 85, 85' are held in place by a similar arrangement, but the stud 89 in this instance also serves as a support for an arm 90. At the outer end of the springs are 40 inturned portions 91 which are adapted to engage in the indentations 81.

The springs 84, 84' and 85, 85' employed in this embodiment of the device are in the form of single leaves, but it is to be understood that any other form of spring may be used, as for instance, 45 the multiple leaf spring of the previous embodiment. Both of these springs and the corresponding springs of the previous embodiment being actually levers as well as springs may also be referred to as levers.

50 The arm 90 is positioned between the switch blades 76 and 77 and is provided with an extension 92 for pivotally mounting it on the stud 89. The arm 90 is of generally arcuate shape with the portion 94 which extends out from the 55 switch blades serving as a handle for operating the switch being provided with an opening 95 by which it can be engaged by a switch hook. The lower end 96 of the arm 90 is positioned between the switch blades and is provided with double 60 cam surfaces 100 and 100'. Balls, or thrust members, 97 are held in place in openings 99 in the switch blades and are positioned between the inner ends of the springs 84, 84' and 85, 85' and the lower end of the arm 90. Reference may be 65 had to Figure 11 for a view of the shape of the cam surface. With the arm 90 in the position shown in Figure 5 the thrust members 97 will be next to the narrow portion 101. To operate the 70 springs 84, 84' and 85, 85', the arm 90 is rotated in a counterclockwise direction to the position shown in Figure 7, during which operation the thrust members 97 will ride up on the cam surfaces 100 and 100' to the widened portion of the arm 90. The result will be to spread the thrust members 97 and the inner ends of the springs

whereby the outer ends of the springs will be biased inwardly bringing the switch blades into high pressure engagement with the stationary contacts. This action of the springs is the same as that of the springs of the previous embodiment, including the feature that when the springs are operated the reaction of each spring caused by the thrust of the thrust member 97 is expended on the spring on the opposite side of the contact bar through its respective spring clamp 86 and stud (87 or 89). The loose relation between the studs 87 and 89 and the switch blades 76 and 77 eliminates any binding effect between them.

It will be noted that in this embodiment there are only two thrust members 97 as distinguished from four in the previous embodiment, one thrust member arranged to operate both springs on one side of the contact bar 75.

A locking dog 104 is pivoted at 105 between the switch blades 76 and 77 and is adapted to engage a lug 106 extending downwardly from the extension 92 on the arm 90. Also positioned between the switch blades is a coil spring 107 supported at 109, one end of which is held against movement by a pin 110, and the other end of which bears against the locking dog biasing it in a counterclockwise direction into locking engagement with the lug 106. A stop 111 supported in a member 112 mounted on the insulator stack 73 is positioned so that when the switch is closed the locking dog 104 will engage the stop which will rotate the locking dog clockwise out of engagement with the lug 106.

Operation of the switch is performed by actuation of the arm 90. Figure 7 shows the switch in closed position with the springs 84, 84' and 85, 85' biasing the switch blades into high pressure engagement with the stationary contacts. When it is desired to open the switch the arm 90 is rotated clockwise until the stop 114 on the arm engages the top of the contact bar 75. By this movement the pressure on the springs 84, 84' and 85, 85' is released and the switch can be opened easily. Continued force exerted on the arm will open the switch. When the switch is in open position the locking dog 104 is in locking engagement with the lug 106 locking the arm 90 in the position shown in Figure 9. The switch can then be closed by a reversal of force on the arm 90. When the switch reaches its closed position the locking dog 104 is engaged by the stop 111 which releases it from engagement with the lug 106, after which the arm 90 may be rotated to the position shown in Figure 7 by continuation of the closing movement whereby the springs 84, 84' and 85, 85' are actuated bringing the switch blades into high pressure engagement with the stationary contacts.

The projections 22 on the switch blades of the first embodiment, and the projections 82 on the switch blades of the second embodiment which constitute the areas of contact between the switch blades and the stationary contacts are substantially more than mere line contacts. The curvature of their surfaces is small and consequently the area of contact is of considerable lateral extent. However, these contact areas are small compared with the total area of the stationary contacts and the ends of the switch blades and it can be readily seen that minor misalignments will not interfere with secure electrical contact. Notwithstanding the small areas of these contacts, the pressure to which they are subjected enhances their current carrying capacity so that

it is not materially less than that of the conductor bars.

Figures 12 and 14, respectively, show two modifications of the invention similar to the two forms 5 shown and described previously, but each with a different kind of contact at the hinge end of the switch blade. In each of the present two forms the hinge end of the switch blade is held under constant pressure in engagement with the corresponding stationary contact. In so far as the present forms of the invention contain parts common with the previous forms, the same reference numerals will apply to both, and the description of those parts and the operation thereof 10 will suffice for both.

Referring to Figure 12, the usual contact bar 15 is pivoted on the conductor bar 12 at 120, and consists of two switch blades 19 and 20, one positioned on either side of the conductor bar 12. The contact areas between the switch blades 19 and 20 and the conductor bar 12 are in the form of annular indentations 121 in the outer surface of the switch blades around the pivot point 120. These indentations result in projections 122 (Figure 13) on the inner surfaces 15 of the switch blades which engage the conductor bar 12. Spring washers 124 with inturned flanges 125 fit into the indented areas 121 and are adapted thereby to bring the contact areas 122 into pressure engagement with the associated conductor bar 12 by means of nuts 127 threaded on studs 126 passing through aligned openings in the conductor bar, switch blades and spring washers. Reference may be had to Figure 13 which shows to good advantage how the various parts are fitted together. This form of switch is similar to that shown in Figure 1, and, although not shown in Figure 13, includes two current paths, each with conductor bars and contact bars. The stud 126 is held in the frame 20 (see Figure 2).

The contact bar 15 is provided with only one set of springs 129, positioned to bias the contact end of the switch blades into engagement with their corresponding conductor bar. The springs 25 are held in place by the usual spring clamp and stud arrangement similarly to Figures 1 and 2, and engage in indented areas 21. The springs are actuated by a cam member 32 operating 30 through ball thrust members 39, as described in connection with Figures 1 and 2. The cam member may be in the form shown, i. e., with two sets of cam surfaces as used in the previous form, so that it will be a standard part for both forms, and, obviously, it may also be designed 35 to have only one set of cam surfaces to accommodate one set of springs.

The switch blades at their hinge ends are held in constant pressure engagement with the conductor bar 12, and the contact ends of the switch 40 blades are adapted, as in the previous form, to be brought into and out of pressure engagement with the conductor bar 14. Even though the switch blades at their hinge ends are held in 45 pressure engagement, this fact does not materially hinder the opening and closing movements 50 of the switch.

Figure 14 shows the type of switch shown in 55 Figure 5, but with the hinge end of the switch blades held in constant pressure engagement with the conductor bar 79 by an arrangement similar 60 to that used in connection with the switch of Figure 12. Reference may be had to Figure 15 which shows the manner in which the various 65 parts of the switch at the hinge end are assembled.

bled. The switch blades are provided with annular indented areas 130 formed in the outer sides thereof which result in corresponding ring projections 131 (see Figure 15) on the inner sides of the switch blades. Spring washers 132 with inturned flanges 134 fit into the indented areas 131 and are adapted to bring the switch blades into pressure engagement with the conductor bar 70 by means of nuts 135 threaded onto stud 136 passing through the various parts. It will be seen that the switch blades are held in constant pressure engagement with the conductor bar, but, as stated in connection with Figure 12, this fact does not materially hinder the opening and closing movements of the switch. The switch blades are provided with a single set of springs 137 for bringing the contact ends of the switch blades into and out of engagement with the conductor bar 71. The arrangement of the remaining parts and the operation is as described in connection with Figure 5.

From the foregoing it will be seen that the invention constitutes a simple device which has the advantageous feature of good electrical contact and can be operated with ease.

While I have shown and described certain specific embodiments of the invention, it is to be understood that the details are not limiting, but illustrative, and all arrangements of parts to meet particular adaptations, and substitution of equivalents, shall be within the spirit and scope of the appended claims.

I claim:

1. A switch comprising, a pair of stationary aligned spaced apart plate-like switch members, a switch blade for interconnecting said switch members including a pair of blade members disposed on opposite sides of said switch members, a pair of lever members pivoted intermediate their ends at positions spaced from the ends of said blade members on the outer sides thereof with the outer ends of said switch members being arranged to engage the adjacent ends of the switch blades individual thereto, and means for moving the inner ends of said lever members outwardly and thereby the outer ends thereof inwardly to move the respective ends of said blade members into contact engagement with the switch member therebetween.

2. A switch comprising, a pair of stationary aligned spaced apart plate-like switch members, a switch blade for interconnecting said switch members including a pair of blade members disposed on opposite sides of said switch members, a pair of lever members pivoted intermediate their ends at positions spaced from the ends of said blade members on the outer sides thereof with the outer ends of said switch members being arranged to engage the adjacent ends of the switch blades individual thereto, ball members engaging the inner ends of said lever members, and cam means operating through said ball members for moving the inner ends of said lever members outwardly and thereby the outer ends thereof inwardly to move the respective ends of said blade members into contact engagement with the switch member therebetween.

3. A switch comprising, a pair of stationary aligned spaced apart plate-like switch members, a switch blade for interconnecting said switch members including a pair of blade members disposed on opposite sides of said switch members, a pair of lever members pivoted intermediate their ends at positions spaced from the ends of said blade members on the outer sides thereof with the outer ends of said switch members being

arranged to engage the adjacent ends of the switch blades individual thereto, a ball member engaging the inner end of each of said lever members, and cam means including a cam surface

5 engaging each of said ball members and operating therethrough for moving the inner ends of said lever members outwardly and thereby the outer ends thereof inwardly to move the respective ends of said blade members into contact engagement with the switch member therebetween.

4. A switch comprising, a pair of stationary aligned spaced apart plate-like switch members, a switch blade for interconnecting said switch members including a pair of flexible blade members disposed on opposite sides of said switch

15 members, a pair of resilient lever members pivoted intermediate their ends at positions spaced from the ends of said blade members on the outer sides thereof with the outer ends of said switch

20 members being arranged to engage the adjacent ends of the switch blades individual thereto, ball members engaging the inner ends of said resilient lever members, and cam means operating through said ball members for moving the inner

25 ends of said resilient lever members outwardly and thereby the outer ends thereof inwardly to move the respective ends of said flexible blade members into contact engagement with the switch member therebetween.

30 5. A switch comprising, a pair of stationary aligned spaced apart plate-like switch members, a switch blade for interconnecting said switch members including a pair of blade members disposed on opposite sides of said switch members.

35 a pair of lever members pivoted intermediate their ends at positions spaced from the ends of said blade members on the outer sides thereof with the outer ends of said switch members being arranged to engage the adjacent ends of the

40 switch blades individual thereto, and means for moving said switch blade to and from switch closed position and as a movement sequential thereto operating said lever members to move the respective ends of said blade members into and out of contact engagement with the switch member therebetween.

45 6. A switch comprising, a pair of stationary aligned spaced apart plate-like switch members, a switch blade pivoted on one of said stationary

50 switch members for interconnecting said switch members including a pair of blade members disposed on opposite sides of said switch members, a pair of lever members pivoted intermediate their ends at positions spaced from the ends of

55 said blade members on the outer sides thereof with the outer ends of said switch members being arranged to engage the adjacent ends of the switch blades individual thereto, and means for moving said switch blade to and from switch closed position and as a movement sequential thereto operating said lever members to move the respective ends of said blade members into and out of contact engagement with the switch member therebetween.

60 7. A switch comprising, two pairs of stationary aligned spaced apart plate-like switch members, a switch blade for each pair of stationary switch members pivoted on one of said stationary switch members for interconnecting its respective pair of switch members, each switch blade including a pair of blade members disposed on opposite sides of its respective pair of switch members, a pair of lever members for each of said blade members and pivoted intermediate their ends at positions spaced from the ends of said blade

members on the outer sides thereof with the outer ends of said switch members being arranged to engage the adjacent ends of the switch blades individual thereto, and common operating means for moving said switch blades to and from switch closed position and as a movement sequential thereto operating said lever members to move the respective ends of said blade members into and out of contact engagement with the switch member therebetween.

8. A switch comprising, a pair of stationary aligned spaced apart plate-like switch members, a switch blade pivoted on one of said stationary switch members for interconnecting said switch members including a pair of blade members disposed on opposite sides of said switch members, a pair of lever members pivoted intermediate their ends at positions spaced from the ends of said blade members on the outer sides thereof with the outer ends of said switch members being arranged to engage the adjacent ends of the switch blades individual thereto, and operating means supported between said blade members for opening and closing the switch and for moving the inner ends of said lever members outwardly and thereby the outer ends thereof inwardly to move the respective ends of said blade members into contact engagement with the switch member therebetween.

9. In a switch, a pair of stationary switch members, a switch blade movable into and out of engagement with said stationary switch members, lever means adapted to bear against said switch blade, cam means adapted to operate said lever means and thereby bring said switch blade into high pressure engagement with said stationary switch members, and operating means for operating said cam means to release the pressure on said switch blade and thereafter in a continuous operation opening the switch.

10. In a switch, a pair of stationary switch members, a switch blade movable into and out of engagement with said stationary switch members, lever means adapted to bear against said switch blade, cam means adapted to operate said lever means and thereby bring said switch blade into high pressure engagement with said stationary switch members, and operating means for closing the switch and thereafter in a continuous operation operating said cam means to bring said switch blade into high pressure engagement with said stationary switch members.

11. In a switch, a pair of stationary switch members, a switch blade comprising a pair of blade members movable into and out of engagement with said stationary switch members on opposite sides thereof, oppositely acting resilient means adapted to bear against said blade members at each point of engagement with said stationary switch members, and cam means adapted to react between oppositely acting resilient means and thereby bring said blade members into high pressure engagement with said stationary switch members.

12. In a switch, a pair of stationary switch members, a switch blade comprising a pair of blade members one on either side of said stationary switch members pivoted for free rotation on one of said stationary switch members and movable into and out of engagement with the other stationary switch member, each of said blade members being provided with a localized area of contact at each end thereof, oppositely acting resilient means at each end of said switch blade adapted to bear against said blade members at

said localized areas of contact, and cam means adapted to react between said oppositely acting resilient means and thereby bring said localized areas of said blade members into high pressure engagement with said stationary switch members.

13. In a switch, stationary switch members, a switch blade movable into and out of engagement with said stationary switch members, lever means for bringing said switch blade into high pressure engagement with said stationary switch members, cam means for operating said lever means, and operating means initially moving in a rectilinear path for operating said cam means and as a continuation thereof in a circumferential path for opening the switch.

14. In a switch, stationary switch members, a switch blade movable into and out of engagement with said stationary switch members, lever means for bringing said switch blade into high pressure engagement with said stationary switch members, cam means for operating said lever means, and operating means initially moving in a circumferential path for closing the switch and as a continuation thereof moving in a rectilinear path for operating said cam means.

15. In a switch, stationary switch members, a switch blade movable into and out of engagement with said stationary switch members, spring means carried by said switch blade and adapted to bear thereagainst for bringing the same into high pressure engagement with said stationary switch members, cam means carried by said switch blade for operating said spring means, and means carried by one of said stationary switch members for operating said cam means.

16. In a switch, stationary switch members, a switch blade movable into and out of engagement with said stationary switch members, said switch blade comprising a pair of blade members one on either side of said stationary switch members, oppositely acting spring means at each end of said switch blade adapted to bias the ends of the blade members thereof into engagement with their corresponding stationary switch members, cam means carried between said blade members and adapted to operate said spring means whereby its force is expended between oppositely acting spring means, and means for operating said cam means.

17. A switch comprising, a pair of stationary aligned spaced apart plate-like switch members, a switch blade pivoted on one of said stationary switch members for interconnecting said switch members including a pair of blade members disposed on opposite sides of said switch members, a pair of lever members pivoted intermediate their ends at a position spaced from the closing end of said switch blade on the outer sides thereof, the outer end of each of said lever members adapted to engage one of said blade members at its point of engagement with the stationary switch member individual thereto, ball members engaging the inner ends of said lever members, and cam means operating through said ball members for moving the inner ends of said lever members outwardly and thereby the outer ends thereof inwardly to move the ends of said blade members at the closing end of said switch blade into contact engagement with the switch member therebetween.

18. A switch comprising, two pairs of stationary spaced apart plate-like switch members, a switch blade for each pair of stationary switch members pivoted on one of said stationary switch members for interconnecting its respective pair of switch members, each switch blade including

a pair of blade members disposed on opposite sides of its respective pair of switch members, a pair of lever members for each pair of said blade members and pivoted intermediate their ends at a position spaced from the closing end of said blade members on the outer sides thereof, each of said lever members adapted to engage its respective blade member at its point of engagement with the switch member individual thereto, and common operating means for moving said switch blades to and from switch closed position and as a movement sequential thereto operating said lever members to move said blade members at their closing end into and out of engagement with the switch member therebetween.

19. A switch comprising, a pair of stationary aligned spaced apart plate-like switch members, a switch blade pivoted on one of said stationary switch members for interconnecting said switch members including a pair of blade members disposed on opposite sides of said switch members, a pair of lever members pivoted intermediate their ends at a position spaced from the closing end of said blade members on the outer sides thereof, said lever members adapted to engage their respective blade members at the closing end thereof to bias them into contact engagement with the switch member therebetween, an arm adapted to operate said lever members and to serve as a handle for opening and closing the switch, and locking means for locking said arm against operation of said lever members during the closing movement of the switch.

20. In a switch, a pair of switch members, a switch blade movable into and out of engagement with said switch members, levers pivoted to act at the ends of said switch blade, an arm pivoted on said switch blade and provided with spreader means, said arm being adapted to operate said levers through said spreader means and thereby bring said switch blade into high pressure engagement with said switch members, said arm also serving as an actuator for opening and closing the switch, and means for locking said arm against operation of said levers during the closing movement of the switch.

21. In a switch, a pair of switch members, a switch blade movable into and out of engagement with said switch members, levers pivoted to act at the ends of said switch blade, an arm pivoted on said switch blade and provided with spreader means, said arm being adapted to operate said levers through said spreader means and thereby bring said switch blade into high pressure engagement with said switch members, said arm also serving as an actuator for opening and closing the switch, means for locking said arm against operation of said levers during the closing movement of the switch, and stop means for releasing said locking means at the end of the closing movement of the switch, after which continued movement of said arm will operate said levers.

22. In a switch, a pair of switch members, a switch blade movable into and out of engagement with said switch members, levers pivoted to act at the ends of said switch blade, an arm pivoted on said switch blade and provided with spreader means, said arm being adapted to operate said levers through said spreader means when the

switch is closed and thereby, through the outer ends of said levers, bring said switch blade into high pressure engagement with said switch members, said arm also serving as an actuator for opening the switch, and stop means on said arm to check the movement thereof with respect to said switch blade after releasing the pressure on said switch blade, following which continued movement of said arm will open the switch.

10 23. In a switch, a pair of switch members, a blade assembly comprising blade elements movable into and out of engagement with said switch members, resilient levers mounted on said blade assembly with their outer ends acting on the ends of said blade elements, thrust members engaging the inner ends of said levers, an arm pivoted on said blade assembly and provided with cam surfaces, said arm being adapted to operate said levers through said cam surfaces and thrust members and thereby, through the outer ends of said levers, bring said blade elements into high pressure engagement with said switch members, said arm also serving as an actuator for opening and closing the switch, and means for locking said arm against operation of said levers during the closing movement of the switch.

24. In a switch, switch members, a switch blade movable into and out of engagement with said switch members, levers pivoted to exert pressure on the ends of said switch blade, cams adapted to operate said levers and thereby bring the ends of said switch blade into high pressure engagement with said switch members, and means for operating said cams.

25. In a switch, switch members, a switch blade movable into and out of engagement with said switch members, said switch blade comprising a pair of blade members disposed on opposite sides of said switch members, levers pivoted to apply pressure to the ends of said blade members, spreader means reacting between said levers for operating said levers and thereby bringing the ends of said blade members into high pressure engagement with said switch members, and means for operating said spreader means.

26. In a switch, a pair of switch members, a switch blade pivoted on one of said switch members and movable into and out of engagement with the other switch member, a lever pivoted to transmit pressure to the closing end of said switch blade, cam means adapted to operate said lever and thereby bring the closing end of said switch blade into high pressure engagement with its corresponding switch member, and means for operating said cam means.

27. In a switch, a pair of stationary switch members, a switch blade pivoted on one of said switch members and movable into and out of engagement with the other switch member, said switch blade comprising a pair of blade members disposed on opposite sides of said switch members, oppositely acting resilient means adapted to exert pressure against said blade members at the closing ends thereof, and cam means adapted to react between said oppositely acting resilient means and thereby bring said blade members at the closing ends thereof into high pressure engagement with the corresponding switch member.

ELIAS S. CORNELL.
